UNITED STATES PATENT OFFICE.

EDOUARD LABITOTIÈRE, OF BEZONS, FRANCE.

MACHINE FOR APPLYING DRIVING-BANDS ON HIGH-EXPLOSIVE SHELLS.

1,346,455.

Specification of Letters Patent. Patented July 13, 1920.

Application filed June 11, 1919. Serial No. 303,514.

To all whom it may concern:

Be it known that I, EDOUARD LABITOTIÈRE, of 2 Quai de Seine, Bezons, Seine, France, engineer, have invented Machines for Applying Driving-Bands on High-Explosive Shells, of which the following is a clear, full, and exact description.

The invention relates to a machine for applying driving bands on high explosive shells, by the action of a falling mass.

This machine, the construction of which is such as to enable shells to be provided with a single or a double driving band, is essentially characterized by the combination of its component elements, viz:

a)—The falling mass,

b)—A hammer arranged under this mass and provided with a peen having a special shape,

c)—A cam adapted to effect the raising of the mass,

d)—A circular operating frame for the shell, controlled by a ratchet so as to effect, at each descent of the hammer, a peripheral advance equal to a predetermined fraction of a revolution,

e)—A pawl brake adapted to hold the hammer stationary in its raised position when the machine is thrown out of gear,

f)—A shell carriage allowing, in case the shell is to receive a second driving band, the displacing of the same to the desired extent for that purpose, when the first driving band has been placed in position.

The two main characteristic features of the machine are as follows:

1. The special shape of the hammer peen. The peen has an oblique and rounded shape, with a radius displaced of about 10° relatively to the axis of descent of the hammer. This shape insures the progressive settling of the small copper bar in the circular groove of the shell; it promotes the lengthening of this small copper bar which is subjected to a powerful drawing out action, so that in the operation of applying driving bands to shells shorter bars may be used, which allow of obtaining a serious economy of material. Finally, the special shape of the hammer peen insures a perfect adherence of the driving band.

2. The above mentioned pawl brake. This automatically operating brake acts upon the

toothed wheel actuating the cam, so as to hold the hammer stationary in its highest position when the machine is thrown out of gear. It is thus possible to replace the shell which has been provided with a driving band by another, without having to effect a special operation for raising the hammer.

The machine is illustrated, by way of example, in the accompanying drawings, in which:

Figure 1 is an elevation of the machine.

Fig. 2 is a front view of the same.

Fig. 3 is an elevation showing the machine on the opposite side from that of Fig. 1.

Fig. 4 is a separate view showing the special shape of the hammer peen.

Figs. 5 and 6 are two different views of the pawl brake which show clearly its mode of operation.

Fig. 7 is a view of one side of the machine.

As illustrated in the drawings, the machine carried by a frame *a*, is operated through a belt and a fast pulley *b*. *c* is the fork adapted to bring the belt on the loose pulley *d* for the throwing out of gear of the machine. The movement is transmitted, reduced by a spur wheel gearing *e* and *f*, to the cam *g* secured on the shaft of the wheel *f*. This cam is adapted to effect the raising of the falling mass *h*, by means of the roller *i* carried by this mass. The latter is provided, at its lower part, with a hammer *j*, the peen of which, as illustrated more particularly in Fig. 4, is of an oblique and rounded shape, with a radius displaced of about 10° relatively to the axis of descent of the hammer *j*, in view of obtaining the above mentioned results; by the expression, with a radius displaced of about 10° relatively to the axis of descent of the hammer, is meant that the center of the rounded part of the peen is not located on the axis of the descent of the peen, but is displaced relatively to the axis, so that the general direction of the operative or active surface of the peen makes with the horizontal plane an angle of 10° , as clearly shown in the drawings, having reference more particularly to Fig. 4, in which the 10° angle is indicated by the dotted line and the inscription 10° .

On the frame *a* of the machine is mounted a carriage *k* which may be moved sidewise by means of a lever *l*. The carriage *k* carries

an operating frame m for the shell n to be provided with a driving band.

The putting into place of the driving band is effected in such conditions that a blow of the hammer is struck for each length of driving band of about $3\frac{1}{2}$ millimeters. For this purpose, the operating circular frame m receives, at each revolution of the machine, that is to say at each descent of hammer j , a 10 rotary movement equal to a fraction of a revolution corresponding to the said length of driving band. This rotary movement is imparted to the circular frame m by a ratchet wheel o having 120 teeth and receiving, at each descent of the hammer j , an advance of one tooth, under the action of a pawl p . The latter is actuated by an incline q arranged within the spur wheel f , through the medium of a system of levers and links 15 r, s, t .

u is the guide for the small copper bars. This guide is constructed in such a manner as to allow of providing the shells with a single or double driving band. The position of the shell n in the operating circular frame m , relatively to the guide u , is determined by a rocking abutment v which is turned down and against which the base of the shell is pressed; the screw which holds the shell stationary in the circular frame m is then strongly tightened.

The shell is supported by four rollers x arranged on each side of the axis of descent of the hammer j and adapted to bear the reactions due to the shock of the hammer.

For the shells which are to be provided with a double driving band, the carriage k is, by means of the lever l , moved sidewise to the necessary extent in such a manner 40 that, when the first driving band has been put into place, the axis of the hammer j is in the axis of the second small copper bar brought in through the second opening of the guide u . A handle nut l' is adapted to hold the carriage k stationary in its two working positions.

The pawl brake m^1 (Figs. 1 and 3) adapted to hold automatically the hammer j in its raised position, when the machine is thrown out of gear, is illustrated separately in Figs. 5 and 6. This brake comprises a member y capable of pivoting about the axis z^1 and carrying a pawl z . On the other hand the brake comprises a leather band x^1 which is constantly and frictionally held, under the action of the spring z^2 , on one of the side faces of the teeth of the spur wheel f . The hammer j is so calculated that the throw should be sufficient to always 50 cause it to rise to the upper position, at the time the machine is thrown out of gear, whatever may be the position it occupies at the time of throwing out of gear. However, as soon as it has reached the upper

position, it falls down by gravity and, when 65 falling down, it reverses the direction of rotation of the wheel f . It is this reversion of movement which brings the pawl z in engagement with one of the teeth of the wheel f which thus is held stationary, so 70 that the hammer is immobilized in its uppermost position. This locking action is produced in the following conditions:

During the rotation of the spur wheel f in the running direction of the machine, the 75 friction of the leather band x^1 on the teeth of the wheel f has for effect to hold the member y in the position illustrated in Fig. 6, so that the pawl z is located on the radius z^1-v^1 . But, at the time of the reversion 80 of the direction of rotation, determined by the fall of the hammer j , this friction causes the member y to pivot about its axis z^1 , thus bringing the pawl z on the radius z^1-v^2 where it is in engagement with one 85 of the teeth of the wheel f . As already explained, the hammer is automatically retained in its upper position by the pawl brake when the machine is thrown out of gear, for the purpose of replacing the shell, to which the driving band has been applied, by another shell, without therefore having to effect a special operation for raising the hammer. In regard to the arrangement and mode of operation and function of the pawl 90 brake, it may be added as has been already set forth that, when the machine is thrown out of gear, the throw of the hammer is sufficient for causing the latter always to rise to the upper part, whatever may be the position 95 it occupies at the time of throwing the machine out of gear. The hammer then tends to descend again by its own weight, and this movement is transmitted by friction to the pawl brake which enters in action and stops the descent. The stoppage is not produced exactly at the top of the stroke of the hammer, but a little below.

The operation of the machine is effected in the following manner:

The shell n is placed on the supporting rollers x , the head of the shell being turned toward the operating circular frame m .

The groove which is to receive the driving band is cleaned by means of a brush by 115 causing the shell to turn on the rollers x .

The rocking abutments v for the base of the shell are turned down, the shell is pressed against these abutments and the screw adapted to immobilize the shell in 120 the circular frame m is tightly screwed on.

The end of the small copper bar is then introduced in its guide u . Its end must extend beyond the axis of the hammer to the extent of about two centimeters in the 125 direction of the rotation of the shell, as indicated by the arrow (Figs. 1 and 3).

The machine is then started and effects

its work in the conditions described and it is stopped when the upper edge of the small copper bar is at a distance of two centimeters from the axis of the hammer *j*.

5 There remains between the ends of this copper bar a play of about two millimeters.

When the shell is to receive a second driving band, the carriage *k* carrying the shell is moved sidewise to an extent of about 10 three centimeters, by means of the lever *l* and it is held stationary by the handle nut *l'* in this second position, then the shell is rotated through 180° for laying the second driving band.

15 The application of the driving band is terminated by hand by means of a hammer of 1 kg. 500.

It is to be understood that any modifications considered useful or advantageous may be made in the construction of the machine described and illustrated, and this without departing from the principle of the present invention.

Claims.

25 1. A machine for applying driving bands on high explosive shells, comprising a falling mass, a hammer placed under this mass and having a peen of special shape, means for effecting the raising of said mass, means for imparting to the shell, at each descent of the hammer, a rotary movement through a predetermined fraction of a revolution, means for maintaining the hammer in its uppermost position when the machine is thrown out of gear, and means, in case the shell is to receive a second driving band, to move said shell to the desired extent for that purpose, after the application of the first driving band.

40 2. A machine for applying driving bands on high explosive shells, comprising a falling mass, a hammer placed under this mass and having an oblique and rounded shape with a radius displaced of about 10° relatively to the axis of descent of the hammer to obtain a progressive settling of the driving band in the circular groove of the shell.

3. A machine for applying driving bands on high explosive shells, comprising a falling mass, a hammer placed under this mass and having an oblique and rounded shape with a radius displaced of about 10° relatively to the axis of descent of the hammer to obtain a progressive settling of the driving band in the circular groove of the shell, and a cam adapted to effect the raising of the mass.

4. A machine for applying driving bands on high explosive shells, comprising a falling mass, a hammer placed under this mass and having an oblique and rounded shape with a radius displaced of about 10° relatively to the axis of descent of the hammer to obtain a progressive settling of the driv-

ing band in the circular groove of the shell, 65 a cam adapted to effect the raising of the mass, and a pawl brake comprising a member capable of pivoting about an axis and carrying a pawl as well as a leather band constantly rubbing against the side face of the spur wheel actuating the raising cam, this device allowing the pawl, when the machine is thrown out of gear, to come in engagement with the spur wheel and to hold it stationary so that the hammer is held in 75 its uppermost position.

5. A machine for applying driving bands on high explosive shells, comprising a falling mass, a hammer placed under this mass and having an oblique and rounded shape 80 with a radius displaced of about 10° relatively to the axis of descent of the hammer to obtain a progressive settling of the driving band in the circular groove, a cam adapted to effect the raising of the mass, a pawl brake comprising a member capable of pivoting about an axis and carrying a pawl as well as a leather band constantly rubbing against the side face of the spur wheel actuating the raising cam, this device allowing 90 the pawl, when the machine is thrown out of gear, to come in engagement with the spur wheel and to hold it stationary so that the hammer is held in its uppermost position, 95 an operating circular frame receiving at each descent of the hammer a rotary movement through a predetermined fraction of a revolution, and a device for actuating this circular frame and comprising a ratchet wheel driven, under the action of a pawl, 100 by an incline arranged within the spur wheel and acting through the medium of levers and links.

6. A machine for applying driving bands on high explosive shells, comprising a falling mass, a hammer placed under this mass and having an oblique and rounded shape with a radius displaced of about 10° relatively to the axis of descent of the hammer to obtain a progressive settling of the driving band in the circular groove of the shell, 105

a cam adapted to effect the raising of the mass, a pawl brake comprising a member capable of pivoting about an axis and carrying a pawl as well as a leather band constantly rubbing against the side face of the spur wheel actuating the raising cam, this device allowing the pawl, when the machine is thrown out of gear, to come in engagement with the spur wheel and to hold it 120 stationary so that the hammer is held in its uppermost position, an operating circular frame receiving at each descent of the hammer a rotary movement through a predetermined fraction of a revolution, a device for actuating this circular frame and comprising a ratchet wheel driven, under the action of a pawl, 115

125 by an incline arranged within

the spur wheel and acting through the medium of levers and links, and a carriage carrying the said circular frame and capable of receiving, by means of a lever, a lateral displacement which allows, when the shell is to receive a second driving band, the bringing of it in a position where the axis of the hammer intersects the axis of the sec-

ond small copper bar brought in through the second opening of the guide for the copper bars.

The foregoing specification of my machine for applying driving bands on high explosive shells, signed by me this nineteenth day of May, 1919.

EDOUARD LABITOTIÈRE.
